ATTORNEY:

UNITED STATES PATENT OFFICE.

THEODORE W. FOSTER, OF PROVIDENCE, RHODE ISLAND.

DESIGN FOR BACK OF BRUSHES.

No. 38,181.

Specification for Design.

Patented Aug. 21, 1906.

Application filed July 16, 1906. Serial No. 326,523. Term of patent 7 years.

To all whom it may concern:

Be it known that I, THEODORE W. FOSTER, a citizen of the United States, residing at Providence, in the county of Providence and State of Rhode Island, have invented a new, original, and ornamental Design for the Back of a Brush, reference being had to the accompanying drawing.

The figure in the drawing is the back view of a brush, showing my design.

I claim—

The ornamental design for the back of a brush, as shown.

THEODORE W. FOSTER.
